No. 610,269.

Patented Sept. 6, 1898.

C. H. HODGKINS.

FOLDING TABLE.

(Application filed Dec. 16, 1897.)

(No Model.)

UNITED STATES PATENT OFFICE.

CURTIS H. HODGKINS, OF NORTHEAST HARBOR, MAINE.

FOLDING TABLE.

SPECIFICATION forming part of Letters Patent No. 610,269, dated September 6, 1898.

Application filed December 16, 1897. Serial No. 662,195. (No model.)

To all whom it may concern:

Be it known that I, CURTIS H. HODGKINS, a citizen of the United States, residing at Northeast Harbor, in the county of Hancock and State of Maine, have invented a new and useful Folding Table, of which the following is a specification.

This invention relates to improvements in folding tables.

10 The object of the present invention is to improve the construction of folding tables and to provide a simple, inexpensive, and efficient one which may be compactly folded when not in use and which may be quickly arranged for use.

15 A further object of the invention is to improve the construction of the locking device for retaining the parts in their operative position and to provide simple and efficient 20 means for accomplishing this result adapted to be quickly engaged with the legs and capable of being retained in such engagement by the weight of the top of the table and its contents, so that there will be no liability of the 25 table accidentally collapsing.

The invention consists in the construction and novel combination and arrangement of parts, as hereinafter fully described, illustrated in the accompanying drawings, and 30 pointed out in the claims hereto appended.

35 In the drawings, Figure 1 is a perspective view of a folding table constructed in accordance with this invention, the top being slightly elevated to show the locking devices. Fig. 2 is a vertical sectional view showing the parts 40 of the table in position for use. Fig. 3 is a side elevation of the table, the parts being folded.

Like numerals of reference designate corresponding parts in all the figures of the drawings.

1 and 2 designate legs arranged in pairs, the members of each pair being connected near their lower ends by transverse bars 3 and being centrally connected to the members of the adjacent pair by pivots 4. The upper ends of the legs 1 are hinged to a transverse cleat 5, which is secured to the lower face of a table-top 6, and the other legs 2 are 45 connected at their upper ends by a cross-bar 7, which is provided near its ends with perforations 8, adapted to be engaged by round

projections or lugs 9 of plates 10. The plates 10, which are arranged on the lower face of the table-top at points diametrically opposite 55 the cleat 5, are perforated for the reception of screws or other suitable fastening devices, and the projections or lugs 9 are offset from the lower face of the table-top.

The table is locked in its position for use by 60 sliding the cross-bar 7 into engagement with the lugs or projections 9, which enter the perforations 8, and as the legs 2 are disposed at an inclination their upper ends rise slightly in withdrawing the cross-bar 7 from the plates 65 10, so that the weight of the table-top and the contents operates to retain the cross-bar in engagement with the lugs or projections and prevents the table from accidentally collapsing. After the legs 2 are disengaged from the 70 plates 10 their upper ends are swung downward against the lower ends of the legs 1, and the table-top, which is hinged to the upper ends of the latter, is adapted to fold against the legs, as clearly illustrated in Fig. 3 of the 75 accompanying drawings.

The top of the table may be strengthened by a longitudinal cleat 11, disposed centrally of the top, at the lower face thereof, and arranged between the plates 10. When this 80 longitudinal cleat is employed, the cross-bar 7 is correspondingly recessed at 12 to receive the cleat, which also supports the legs 2 against lateral movement and serves as a guide for them.

85 It will be seen that the table possesses the following advantages:

The locking mechanism is simple, strong, and comparatively inexpensive in construction. It is easily manipulated, and there is no 90 liability of the table accidentally collapsing, as the weight upon the top of the table operates in a measure to retain the cross-bar in engagement with the lugs of the plates.

The table may be quickly and compactly 95 folded when it is not in use, and it is readily unfolded and arranged for use.

Changes in the form, proportion, and minor details of construction may be resorted to without departing from the spirit or sacrificing any of the advantages of this invention.

100 What I claim is—

1. A folding table comprising a top, the oppositely-inclined legs arranged in pairs and

- centrally pivoted together, the upper ends of one pair of legs being hinged to the top, a cross-bar connecting the upper ends of the other pair of legs and provided with a perforation, and a plate secured to the lower face of the table-top and provided with an inwardly-extending projection or pin arranged to engage the perforation of the cross-bar, substantially as and for the purpose described.
- 10 2. A folding table comprising a top, the oppositely-inclined legs arranged in pairs and centrally pivoted together, the upper ends of one pair being hinged to the top, a cross-bar connecting the upper ends of the other pair and provided with perforations and having a

recess between them, plates secured to the lower face of the top and having inwardly-extending projections engaging the perforations of the cross-bar, and a longitudinal cleat mounted on the lower face of the top, arranged between said plates and fitting in the recess of the cross-bar, substantially as described.

In testimony that I claim the foregoing as my own I have hereto affixed my signature in the presence of two witnesses.

CURTIS H. HODGKINS.

Witnesses:

C. C. PERRY,
Mrs. C. C. PERRY.
